DESIGN FOR A TOY CART

Robert C. Flynt, Winston-Salem, N. C.

Application July 29, 1943, Serial No. 110,790

Term of patent 3½ years

To all whom it may concern:

Be it known that I, Robert C. Flynt, a citizen of the United States, residing at Winston-Salem, in the county of Forsyth and State of North Carolina, have invented a new, original, and ornamental Design for a Toy Cart, of which the following is a specification, reference being had to the accompanying drawing, forming part thereof.

ing my new design, the appearance from the other side being the same;

Figure 2 is a front elevation; and

I claim:

The ornamental design for a toy cart, as shown and described.

ROBERT C. FLYNT.
